UNITED STATES PATENT OFFICE.

PERCY M. ELLIOTT, OF CHICAGO, ILLINOIS.

RAZOR-STROP.

1,072,590.

Specification of Letters Patent. Patented Sept. 9, 1913.

Application filed October 10, 1912. Serial No. 725,028.

To all whom it may concern:

Be it known that I, PERCY M. ELLIOTT, a citizen of the United States, residing at Chicago, in the county of Cook and State of Illinois, have invented certain new and useful Improvements in Razor-Strops, of which the following is a specification.

My invention relates in general to razor strops, and more particularly to that type 10 of razor strops in which the strops are mounted upon the supporting frame.

It is often inconvenient to find a suitable support upon which to hang the usual flexible razor strop, and hence it is desirable that 15 the strop should be mounted upon a portable supporting frame. The objection to this latter type of razor strop, as heretofore constructed, is that when the strops wear out the device becomes useless and must be 20 thrown away.

The object of my invention is to provide a razor strop of the type in which the strops are mounted upon a portable frame, in which the strops may be readily placed upon the 25 supporting and stretching frame, and may be easily removed when worn out and replaced by new strops, thereby permitting the same supporting frame to be repeatedly used by merely renewing the strops when 30 necessary.

A further object of my invention is to provide a razor strop which will be simple and durable in construction and convenient in use.

My invention will be more fully disclosed 35 hereinafter with reference to the accompanying drawing, in which the same is illustrated as embodied in a convenient and practical form, and in which—

Figure 1 is a side elevational view, the adjusting turnbuckle being shown in section; Fig. 2, a plan view; Fig. 3, a sectional detail through one end of the device; and Fig. 4, an end elevational view.

The same reference characters are used to 45 designate the same parts in the several figures of the drawing.

Reference characters A' and A² indicate 50 heads spaced apart and adjustably connected. The heads are provided with inwardly projecting rods b' and b² screw threaded at their adjacent inner ends which are engaged by a turnbuckle B. The heads are made of any suitable material, prefer- 55 ably aluminum, with the rods cast integrally with the respective heads. The outer sur-

faces of the heads are concave, preferably V-shaped in cross section, to receive blocks C' and C² which are preferably made of wood so as to permit the ends of the strops 60 being tacked thereto.

In order to permit the convenient connection of the blocks with the corresponding heads, and at the same time to allow the blocks to be readily applied to and removed 65 from the heads, each of the heads is provided with inwardly projecting beads a' and a² along the outer edges of the concavity therein. A flange a is also provided at one end of the concave recess in each head which 70 serves as a stop to engage the block when it is inserted from the opposite side of the recess. The side edges of each block are curved to surround the beads a' and a² on the edges of the head. 75

D' and D² designate razor strops, which may be conveniently made of different materials, such, for instance, as leather and canvas. The ends of the strops extend around the heads and blocks and are secured to the 80 latter by suitable fastening devices, such, for instance, as tacks F.

The manner of assembling and using my improved razor strop will be readily understood from the foregoing description. The 85 blocks C' and C² are seated within the recesses in the outer ends of the heads A' and A² by engaging the grooves in the blocks with the beads at the outer edges of the recesses in the heads. The blocks are then 90 slid relatively to the heads until the stop flanges a are engaged. The strops are then placed upon opposite sides of the heads and their ends tacked to the blocks. The turnbuckle is then manipulated so as to separate 95 the heads and thereby impart to the strops the desired tension.

It will be observed from the above description that in my improved razor strop the strops may be readily removed when 100 worn out and new strops applied by merely withdrawing the tacks from the ends of the old strops and then placing new strops in position upon the heads and block and driving tacks through them into the blocks. It 105 will be further observed that the blocks when worn out through driving tacks into them may be readily replaced by new blocks. A further advantage in forming the blocks to which the strops are secured separate 110 from the heads is that the heads may be made of metal and an ornamental polish

imparted to them, while the blocks being made of wood permit the convenient securing to them of the ends of the strops.

While I have described more or less in detail the specific form in which I have illustrated my invention as embodied, yet I do not wish to be understood as limiting myself thereto, as I contemplate changes in form, proportion of parts, and substitution of equivalents, as circumstances may require, or as may be deemed expedient.

What I claim is:

1. In a razor strop, the combination with a pair of heads having recesses in their outer surfaces, of means for adjustably connecting said heads, blocks removably engaging within said recesses, and strops secured to said blocks.
2. In a razor strop, the combination with a pair of heads having recesses in their outer surfaces, of means for adjustably con-

necting said heads, beads along the outer edges of said recesses, blocks removably fitting within said recesses and having grooves engaging said beads, and strops secured to 25 said blocks.

3. In a razor strop, the combination with a pair of heads having recesses in their outer surfaces, of means for adjustably connecting said heads, beads along the outer edges of said recesses, blocks removably fitting within said recesses and having grooves engaging said beads, a flange formed at one side of each of said recesses against which the block seated therein engages, and strops 30 secured to said blocks.

In testimony whereof, I have subscribed my name.

PERCY M. ELLIOTT.
